(57) **CLAIM**

The ornamental design for a bottle, as shown and described.

DESCRIPTION

FIG. 1 is a perspective view of my new bottle;

FIG. 2 is a top view thereof;

FIG. 3 is a bottom view thereof;

FIG. 4 is a front view thereof;

FIG. 5 is a left side view thereof;

FIG. 6 is a rear view thereof; and,

FIG. 7 is a right side view thereof.

The dot-dot-dash-dot-dot-dash broken lines shown in the drawing views are included for the purpose of showing environmental structure that forms no part of the claimed design.

The horizontal dot-dot-dot-dot broken line at the bottom of the sidewall in the drawings represents the bottom boundary of the claimed design.
